Primary Examiner—M. N. Pandozzi(74) *Attorney, Agent, or Firm*—Hodgson Russ LLP(57) **CLAIM**

The ornamental design for beverageware, as shown and described.

DESCRIPTION

FIG. 1 is a perspective view of beverageware showing our new design;

FIG. 2 is a right-hand side elevational view thereof, the left-hand side view thereof being a mirror image of the side shown;

FIG. 3 is a rear elevational view thereof;

FIG. 4 is a front elevational view thereof;

FIG. 5 is a bottom plan view thereof; and,

FIG. 6 is a top plan view thereof.

The broken lines in the drawings are for illustrative purposes only and form no part of the claimed design.
